PAPER FEEDING, CUTTING, AND
REGISTERING MECHANISM

Nelson E. Funk, Kalamazoo, Mich.

Application January 12, 1946, Serial No. 640,798

14 Claims. (Cl. 164—68)

1

This invention relates to improvements in paper feeding, cutting and registering mechanism.

The main objects of this invention are:

First, to provide a paper cutting, feeding and registering mechanism which is well adapted for delivering paper in the form of sheets to a printing press in registering relation thereto.

Second, to provide a machine or apparatus for feeding paper from a roll to a cutter and from the cutter in side and end registering relation to a printing press or other machine.

Third, to provide a machine of this character in which the paper may be readily adjusted for cutting and delivering of sheets of considerable variation in length.

Fourth, to provide an apparatus of this character in which the sheets are cut to very accurate lengths and are delivered in accurate register.

Fifth, to provide a structure embodying these several advantages which is comparatively simple and at the same time positive in performing its functions of feeding, cutting and registering delivery.

Objects relating to details and economies of the invention will appear from the description to follow. The invention is defined and pointed out in the claims.

A preferred embodiment of the invention is illustrated in the accompanying drawings, in which:

Fig. 1 is a side elevation of a machine embodying my invention as applied to a printing machine, only such portions of a printing machine being illustrated as are deemed desirable to show the functioning relation, and various parts being shown mainly in conventional form.

Fig. 2 is an enlarged fragmentary plan view of parts of the structure shown in Fig. 1, parts being shown in horizontal section.

Fig. 3 is an enlarged fragmentary view partially in transverse section on line 3—3 of Fig. 2 showing details of the feed and registering mechanism.

Fig. 4 is an enlarged fragmentary view mainly in longitudinal section on line 4—4 of Fig. 2.

Fig. 5 is an enlarged fragmentary vertical section through the cutter rolls or cylinders, with the knives in cutting position.

Fig. 6 is an enlarged fragmentary view in section on line 6—6 of Fig. 2 showing details of the driven sheet feed roller which is provided with an overrunning or one way clutch.

Fig. 7 is an enlarged fragmentary view partially in longitudinal section illustrating certain details of the paper delivery and registering means.

2

Fig. 8 is a plan view showing diagrammatically the relative positions of the paper web and cutting knife and the cut made by the knife.

In the accompanying drawings, 1 represents the frame of a printing press, 2 the impression cylinder, 3 the type or printing cylinder, and 4 the transfer cylinder for transferring the sheets from the registry table or bed 5 to the impression cylinder. The transfer cylinder 4 has a registering stop 6. The sheet grippers or other pickup means of the transfer cylinder are not illustrated as they form no part of this invention and are understood by those skilled in the art to which the invention relates. The stop 6 is adjustable and suitable means for effecting this adjustment are likewise known in the art and are not shown.

The frame 7 is designed to support various moving parts to be described. Side rails 8 extend between the frame of the printing press and this frame 7 and support the feed bed or table 5. The frame 7 is provided with bearings 9 to receive the roll supporting spindle 10 of the roll of paper 11. The web of paper is provided with a suitable brake or drag means not illustrated. The paper is drawn from the roll 11 and delivered into a loop 12 by a paper feed unit comprising the coacting feed rollers 13 and 14, the feed roller 13 being the driven feed roller and the roller 14 being a pressure roller. In the embodiment illustrated the roller 14 is in the form of a plurality of wheels having rubber rims 15. The shaft 16 of these pressure wheels is carried on arms 17 on the transverse rod 18. Arms 19 on this transverse rod 18 support the thrust springs 20.

From the loop 12 the web designated by the numeral 21 passes over the aligning guide 22 to the second feed unit comprising the driven feed roller 23 and coacting pressure roller 24 which is desirably of the same structure as the pressure rollers described for the first feed unit. The feed roller 23 is provided with a shaft 25 having a sprocket gear 26 while the shaft 27 of the feed roller 13 is provided with a sprocket wheel 28. The shaft of the pressure rollers 24 is carried by arms 17 on the transverse rod 29 corresponding to the rod 18 and has the pressure means as described for the first unit.

The web is advanced by the second feed unit to the coacting rotary cutters designated generally by the numerals 31 and 32, these cutters being provided with shafts 33 and 34 positioned at an angle to the path of travel of the web as shown in Fig. 2. The rotary cutters are provided with disk-like end bearers 37 and axially spaced feed disks or bearers 38. The bearers 37 are of the diameter of the meshing drive gears 39 on the

shafts 33 and 34. The disks or bearers of the lower cylinder or cutter are provided with segmental gripping portions 40 while those of the upper cutter or cylinder are provided with coacting segmental gripping portions 41 of rubber or resilient material, the gripping segments 40 being of non-resilient material. The knives 35 and 36 are set in these segmental gripping portions so that the paper is gripped as it is subject to the knives or while the paper is being cut.

It will be noted that the gripping portions are disposed in angularly stepped relation about the rotary cutters. In the embodiment of the invention illustrated, which is a commercial embodiment, the knives are disposed at an angle of approximately one and one-half degrees angular relation to the axes of the rotary cutters or cylinders and are set at the same angle so that the knives start cutting at one edge of a web and make a smooth cut across the web, the result being a straight right-angled cut across the web. The gripping segments are of such length as to grip the web from the beginning to the end of the cut so that there is no relative slippage. The leading edges of the gripping segments 40 and 41 will first grip the web as the segments are rotated into coacting relationship on opposite sides of the web. As rotation of the cutter progresses and the knives are brought into lapping shearing engagement, there will be some depression of the leading portion of the resilient gripping segments ahead of the blades by reason of engagement of the lower blade with the resilient gripper ahead of the upper blade as is illustrated in Fig. 5. However, before retraction or compression of the leading portion of the resilient gripper has progressed sufficiently to release the newly severed portion of the web, the rear trailing portion of the resilient gripper will have moved into gripping relation with the web behind the blades.

At the rear of the cutter unit I provide a sheet feed unit which also serves to support the end of the web at the rear of the cutter unit during the cutting operation. This unit comprises the feed roller 42 mounted on the shaft 43 and having a driving connection therewith. The coacting pressure roller 44 is of the rubber tired wheel type described for the previously described feed units and its shaft 44 is carried by arms 45 on the rockshaft 46.

This sheet feed unit is mounted on supports or slides 47 adjustable longitudinally of the side rails 8, the side rails being slotted at 48 to receive the clamping bolts 49 by means of which the supports or slides are secured in their adjusted positions. As the cutter begins making a cut the pressure wheels 44 are lifted from pressure contact with the web. The means for doing this in the embodiment illustrated comprises the cam 50 on the shaft 34 of the lower cutter cylinder, this cam coacting with a cam follower roller 51 on the lever 52 which is connected by the link 53 to the arm 54 on the rockshaft 46. The spring 55 holds the follower against the cam and serves to lift the pressure roller when it is released by the cam. The length of the link 53 is adjustable as at 53A to accommodate adjustments of the slides 47 of the feed unit.

To prevent any undue stress on the web while it is engaged by the gripping segments the sprocket wheels 26 on the feed roller shaft 25 are desirably provided with an overrunning clutch which may be of the roller type illustrated in Fig. 6. The control of the pressure roller 44 is such that on the completion of the cut and release

of the web by the cutter the pressure roller 44 is brought into contact with the cut sheet which is advanced on the feed table 5 until its edge contacts the feed roller 58 of the delivery and registering unit. This feed roller 58 is driven at a slightly higher circumferential speed than the transfer cylinder 4.

The driving connections illustrated include the sprocket 56 on the shaft 57 of the roller 58 which is connected by the sprocket chain 60 to a sprocket 61 on the shaft 43. The shaft 43 is provided with a sprocket wheel 62 which is connected by the sprocket chain 63 to the sprockets on the feed roller shafts 25 and 27. One of the gears 39 of the rotary cutter is connected by an intermediate gear 66 to a gear 67 on the shaft 43. Primary driving energy is delivered to one of the gears 39 from a suitable source, not shown. To vary the length of the sheet cut a gear 66, which meshes with gear 67 which drives a sprocket at 62, which drives a sprocket at 28 (Fig. 2) on the feed roll 43 can be changed to another gear 66 having a different number of teeth thereon, if the shaft on which gear 66 is mounted is made adjustable as to position on the frame. This will effect a variation in the feed of the web and so vary the lengths cut by the uniformly driven cutter roll. The roll 58 has a resilient or yielding face 59.

Feed pressure balls 68 are provided to coact with the roller 58, these balls being rotatably supported in holders 69 carried on the cross member 70 mounted on the side rails 8. These pressure rollers permit lateral shifting of the sheet as well as the feeding thereof. As the sheet engages the feed roller 58 it is drawn out of contact with the feed roller 42 and coacting pressure roller 44, a portion of the sheet being supported by the table. At the rear of the roller 58 I provide a suction registering means comprising the shaft 71 which is connected by the gears 72 and the meshing gears 73 to the shaft 57 of the roller 58. This shaft 71 is mounted for axial movement and is provided with a yielding faced sheet supporting roller 74.

At each end of this roller 74 I provide a suction drum 75, these suction drums being fixed to the shaft and each having a peripheral series of suction holes 76 preferably arranged in staggered relation. These suction drums embrace the suction heads 77 which are non-rotatably mounted on brackets 78 carried by the cross piece 10. The suction heads have restricted recess-like chambers 79 with which the suction holes of the drums are successively brought into register as the drums rotate. The suction heads are connected by flexible hose 80 to the branch pipe 81 connected to a suitable source of vacuum, as the vacuum pump 82 shown conventionally in Fig. 2. The pipe or conduit 81 is provided with a solenoid controlled valve 83 also shown conventionally in Fig. 2.

The shaft 71, being supported for axial movement in its bearings 34, is actuated to laterally register the sheets, and this is in timed relation to the rotation of the transfer cylinder 4. The means illustrated for accomplishing this comprises a cam 85 on the shaft 86 of the transfer cylinder, this cam coacting with a lever 87 provided with a roller follower 88. The lever is connected by the link 89 to one arm of the bell crank lever 90 pivoted at 91; the other arm of the lever being forked to engage the shifting collar 92 of the shaft 71.

As the suction feed roller is shifted axially, the web is moved transversely, the pressure rollers 68

permitting this shifting without undue stress on the sheet or wrinkling of the sheet. The shifting of the sheet laterally brings it into contact with the switch actuating arm 93 of the switch 94 shown conventionally in Fig. 2, the connection for the switch to the solenoid actuated valve 83 being conventionally shown at 95. The sheet is advanced against the positioning stop 6 of the transfer roller and thus properly registered longitudinally, and at the same time is shifted laterally and properly registered transversely.

I have illustrated an embodiment of my invention as I have adapted the same for feeding and registering in a printing press. My invention however may be readily adapted for use in other relations or in other paper conveying machines without bringing the sheets to a stop as is usual in a conventional paper feeding and cutting mechanism. Various parts are illustrated more or less conventionally in the accompanying drawing and I have not illustrated the source of power. This may be applied through the gear 72, for example, or through a pulley provided for the purpose on the shaft 71, or through one of the gears 39.

I have not illustrated or described the various adaptations or embodiments of my invention contemplated as it is believed this disclosure will enable those skilled in the art to adapt my invention as may be desired.

Having thus described my invention what I claim as new and desire to secure by Letters Patent is:

1. In a machine of the class described, the combination of cutter means comprising coacting rotary cutters driven at the same speed and having axially spaced feed disks, the disks having angularly stepped work gripping segments, the segments of one cutter being resilient, those of the other being non-resilient, knives mounted in said work gripping segments in angularly inclined relation relative to the axes of the cutters, means for aligning and feeding a web to said cutter means, a sheet feed means at the rear of said cutter means positioned to receive the sheets therefrom and comprising supports adjustable to and from the cutter means, a driven shaft mounted on said supports, a sheet feed roll on said shaft, a press roller shaft, a rockshaft mounted on said supports and provided with supporting arms for said press roller shaft, a press roll mounted on said press roller shaft to coact with said sheet feed roll, a cam on the shaft of one of said cutters, a lever provided with a follower coacting with said cam, and a second arm on said rockshaft having a link connection to said lever, said cam being arranged so that the sheet feed means is non-operating during the cutting period of the cutter means.

2. In a machine of the class described, the combination of cutter means comprising coacting rotary cutters driven at the same speed and having axially spaced feed disks, the disks having angularly stepped work gripping segments, the segments of one cutter being resilient, those of the other being non-resilient, knives mounted in said work gripping segments in angularly inclined relation relative to the axes of the cutters, means for aligning and feeding a web to said cutter means, a sheet feed means at the rear of said cutter means positioned to receive the sheets therefrom and comprising supports adjustable to and from the cutter means, a driven shaft mounted on said supports, a sheet feed roll on said shaft, a press roller shaft, a rockshaft mounted

on said supports and provided with supporting arms for said press roller shaft, a press roll mounted on said press roller shaft to coact with said sheet feed roll, and means for actuating said rockshaft to disengage the press roll timed with the cutting of the web.

3. In a machine of the class described, the combination of cutter means comprising rotary cutters driven at the same speed and having axially spaced feed disks, the disks having angularly stepped work gripping segments, the segments of one cutter being resilient, those of the other being non-resilient, knives mounted in said work gripping segments in angularly inclined relation

10 relative to the axes of the cutters, first and second web feed units disposed in advance of said cutter means and each comprising a feed roller and coacting pressure roller, the first feed unit being adapted to deliver the web into a loop in 15 advance of the second feed unit, the second feed unit delivering to the cutters, web aligning means disposed in advance of the second feed unit to receive the loop and align the web as it enters the second feed unit, and a sheet feed means at 20 the rear of said cutter means position to receive the sheets therefrom comprising a sheet feed roller, a press roller coacting therewith, and a means acting to disengage said press roller during the cutting period of the cutter means.

30 4. In a machine of the class described, the combination of cutter means comprising coacting rotary cutters driven at the same speed and having axially spaced feed disks, the disks having angularly stepped work gripping segments, the segments of one cutter being resilient, those of the other being non-resilient, knives mounted in 35 said work gripping segments in angularly inclined relation relative to the axes of the cutters, means for aligning and feeding a web to said cutter means, and a sheet feed means at the rear of said cutter means positioned to receive the sheets therefrom comprising a sheet feed roller, a press roller coacting therewith, and means acting to disengage said press roller during the cutting period of the cutter means.

45 5. In a machine of the class described, the combination of cutter means comprising coacting rotary cutters driven at the same speed and having axially spaced feed disks, the disks having angularly stepped work gripping elements, the segments of one cutter being resilient, those of the other being non-resilient, knives mounted in 50 said work gripping segments in angularly inclined relation relative to the axes of the cutters, first and second web feed units disposed in advance of said cutter means and each comprising a feed roller and coacting pressure roller, the first feed unit being adapted to deliver the web into a loop in advance of the second feed unit, the 55 second feed unit delivering to the cutters, web aligning means disposed in advance of the second feed unit to receive the loop and align the web as it enters the second feed unit, a sheet feed means at the rear of said cutter means positioned to receive the sheets therefrom comprising a driven shaft, a sheet feed roll on said shaft having a connection thereto, a press roller shaft, a rockshaft provided with supporting arms for said press roller shaft, a press roll mounted 60 on said press roller shaft to coact with said sheet feed roll, a cam on the shaft of one of said cutters, a lever provided with a follower coacting with said cam, and a second arm on said rockshaft having a link connection to said lever, said 65 cam being arranged so that the sheet feed means 70 75

is non-operating during the cutting period of the cutter means.

6. In a machine of the class described, the combination of cutter means comprising coacting rotary cutters driven at the same speed and having axially spaced feed disks, the disks having angularly stepped work gripping segments, the segments of one cutter being resilient, those of the other being non-resilient, knives mounted intermediate of the angularly spaced ends of said work gripping segments in angularly inclined relation relative to the axes of the cutters, and means for aligning and feeding a web to said cutter means.

7. In a machine of the class described, the combination of a cutter means including rotary cutters having axially spaced angularly stepped coacting work gripping segments, the segments of one cutter being resilient, knives mounted in said work gripping segments in angularly inclined relation to the axes of the cutters, means for aligning and feeding a web to said rotary cutters, a sheet feed means disposed at the rear of said cutter means and comprising a feed roller provided with a driving means, a coacting press roller shiftable to and from operative relation to said feed roller, and means for shifting said press roller in timed relation to the cutters whereby the sheet feed means is non-operating during the cutting period of the cutter means.

8. In a machine of the class described, the combination of a cutter means including rotary cutters having axially spaced angularly stepped coacting work gripping segments, the segments of one cutter being resilient, knives mounted in said work gripping segments in angularly inclined relation to the axes of the cutters, a sheet feed means disposed at the rear of said cutter means and comprising a feed roller provided with a driving means, a coacting press roller shiftable to and from operative relation to said feed roller, and means for shifting said press roller in timed relation to the cutters whereby the sheet feed means is non-operating during the cutting period of the cutter means.

9. In a machine of the class described, the combination of a cutter means including rotary cutters having knives mounted in angularly inclined relation to the axes of the cutters, a sheet feed means disposed at the rear of said cutter means and comprising a feed roller provided with a driving means, a coacting press roller shiftable to and from operative relation to said feed roller, and means for shifting said press roller in timed relation to the cutters whereby the sheet feed means is non-operating during the cutting period of the cutter means.

10. In combination, coacting rotary cylinders having axially spaced angularly stepped coacting work gripping segments, the segments of one roller being resilient, and knives mounted intermediate of the angularly spaced ends of said work gripping segments in angularly inclined relation to the axes of the cutters.

11. In a machine of the class described, the combination of cutter means for cutting a web into sheets while the web is in movement, the cutter means also constituting web advancing means, a sheet feed means at the rear of said

cutter means positioned to receive the sheets therefrom, said sheet feed means comprising a sheet feed roller, a press roller shiftable to and from operative relation to said sheet feed roller, and means for shifting said press roller timed to render the sheet feed means non-operating during the cutting period of the cutter means.

12. In a machine of the class described, the combination of cutter means for cutting a web into sheets while the web is in movement, the cutter means also constituting web advancing means, first and second web feed units disposed in advance of said cutter means and each comprising a feed roller and coacting pressure roller, the first feed unit being adapted to deliver the web into a loop in advance of the second feed unit, the second feed unit delivering to the cutter means, web alining means disposed in advance of the second feed unit to receive the loop and aline the web as it enters the second feed unit, a sheet feed means at the rear of said cutter means positioned to receive the sheets therefrom, said sheet feed means comprising a feed roller having a driving connection, a press roller shiftable to and from operative relation to said feed roller, and means for shifting said press roller timed to render the sheet feed means non-operating during the cutting period of the cutter means.

13. In a machine of the class described, the combination of cutter means for cutting a web into sheets while the web is in movement, a sheet feed means at the rear of said cutter means positioned to receive the sheets therefrom and mounted for adjustment to and from the cutter means, said sheet feed means comprising a feed roller having a driving connection, a press roller shiftable to and from operative relation to said feed roller, and means for shifting said press roller timed to render the sheet feed means non-operating during the cutting period of the cutter means.

14. In a machine of the class described, the combination of cutter means for cutting a web into sheets while the web is in movement, a sheet feed means at the rear of said cutter means positioned to receive the sheets therefrom, said sheet feed means comprising a feed roller having a driving connection, a press roller shiftable to and from operative relation to said feed roller, and means for shifting said press roller timed to render the sheet feed means non-operating during the cutting period of the cutter means.
